UNITED STATES PATENT OFFICE

ODE D. JENNINGS, OF SCHAUMBURG TOWNSHIP, COOK COUNTY, ILLINOIS, ASSIGNOR
TO O. D. JENNINGS & COMPANY, OF CHICAGO, ILLINOIS, A CORPORATION OF ILLINOIS

DESIGN FOR A VENDING MACHINE

Application filed March 15, 1933. Serial No. 47,464. Term of patent 7 years.

To all whom it may concern:

Be it known that I, ODE D. JENNINGS, a citizen of the United States, residing in Schaumburg township, in the county of Cook, and State of Illinois, have invented a new, original, and ornamental Design for a Vending Machine, of which the following is a specification, reference being had to the accompanying drawing, forming part thereof.

The figure is a perspective view of the article illustrating my new design.

I claim:

The ornamental design for a vending machine, as shown.

In witness whereof, I hereunto subscribe my name, this 1st day of March, 1933.

ODE D. JENNINGS.
